UNITED STATES PATENT OFFICE.

WILLIAM H. SMYTHE, OF WINTHROP, MASSACHUSETTS.

DESIGN FOR A STATIONERY-CONTAINER.

54,513.

Specification for Design.

Patented Feb. 17, 1920.

Application filed May 12, 1919. Serial No. 296,714. Term of patent 3½ years.

To all whom it may concern:

Be it known that I, WILLIAM H. SMYTHE, a citizen of the United States, residing at Winthrop, in the county of Suffolk and State of Massachusetts, have invented a new, original, and ornamental Design for Stationery-Containers, of which the following is a specification, reference being had to the accompanying drawing, forming a part thereof.

The figure is a perspective view of a stationery container, showing my new design.

I claim:

The ornamental design for a stationery container, as shown.

WILLIAM H. SMYTHE.
